UNITED STATES PATENT OFFICE.

RICHARD H. WELLES, OF KENOSHA, WISCONSIN. ASSIGNOR TO THE BADGER BRASS MFG. CO., OF KENOSHA, WISCONSIN, A CORPORATION OF WISCONSIN.

HEADLIGHT.

No. 913,997.

Specification of Letters Patent.

Patented March 2, 1909.

Application filed September 19, 1907. Serial No. 393,625.

To all whom it may concern:

Be it known that I, RICHARD H. WELLES, a citizen of the United States, residing at Kenosha, county of Kenosha, State of Wisconsin, have invented certain new and useful Improvements in Headlights, of which the following is a specification.

This invention relates to improvements in head lights for automobiles.

10 Among the salient objects of the invention are to provide a construction which presents as far as practicable a smooth exterior surface substantially free from protruding screws or rivets, so that it may be more readily polished and at the same time presents a more finished appearance; to provide a construction in which the union members which receive the securing rivets or screws are substantially concealed within the interior of the head light shell; to provide a construction which can be readily assembled or taken apart; and in general to provide an improved construction of the character referred to.

25 The invention will be readily understood from the following description reference being had to the accompanying drawings in which—

Figure 1 shows a longitudinal vertical sectional view of my improved head light, parts being broken away to show the details of construction. Fig. 2 is a cross-section taken through lines 2—2 of Fig. 1 looking in the direction of the arrows. Fig. 3 is a cross-section taken through lines 3—3 of Fig. 1. Fig. 4 is an enlarged detail view showing the manner of securing the end wall to the main body of the shell.

Referring to the drawings, 1 designates as 40 a whole the head light comprising a cylindrical barrel or side body 2, a convex end wall 3, and a hinged flaring front member 4. The head light is also provided with the usual burner 6, air vent 7, reflector 8, and 45 front glass or crystal 9.

The reflector is of slightly less diameter than the interior of the shell and it is necessary that it be situated and supported at the proper focal distance from the burner. It is 50 also desirable that the end wall be outwardly convex in order to give a more finished effect, and that the reflector be spaced away from the shell to lessen the liability of breakage. To this end I provide a combined joining ring 55 reflector seat 10, which takes the form of an

interiorly concave ring which is so shaped as to conform to the rear surface of the reflector when the latter is in position. The inner periphery of the ring 10 is struck up to form a confining flange 11 which fits within an annular shoulder 12 formed in the rear end wall 3. The outer periphery of the ring 10 is bent radially outward at 13 and then forwardly at right angles thereto to form a cylindric clamping extension 13' which fits snugly over the rear end of the side body 2. The edge of the extension 13' is formed into an outturned bead 13'', crimped over and interlocked with the end wall 3; the latter being provided at its periphery with a right angled extension 14 engaged by the bead. The reflector is confined in its seat in the seat ring 10 by means of a confining ring 17. It will be noted that the periphery of the reflector is shaped to form an inwardly converging shoulder 18 and the ring 17 is clamped against this shoulder. To this end the ring 17 is provided at its outer or larger periphery with a radial flange 19 which fits against the corresponding portion 13 of the ring 10 when the parts are in assembled position. Upon the back side of the ring 10 are soldered a plurality of nuts 20 which are threaded and arranged in register with apertures 21 through the ring 10, and corresponding apertures 22 in the ring 17. The reflector being seated between the rings 10 and 17, the latter are clamped together by suitable screws 24 inserted through said parts and into the nuts.

90 Heretofore it has been the practice to secure the end wall to the main body of the shell by uniting the parts together by rivets or screws protruding through both the end wall and the main body. In order to obviate 95 the necessity of such a construction and as an important feature of my device I provide for detachably uniting the side member 2 and end wall 3 by brackets arranged within the shell of the headlight. To this end a plurality 100 of right-angled brackets 23 are secured to the inner wall of the side body 2 and so arranged as to register with alternate ones of the nuts 20. Each of these brackets 23 is suitably apertured for the reception of a confining 105 screw 24. The end wall 3 together with the reflector may now be secured to the main body of the shell by slipping the extension 13' of the ring 10 over the rear end of the side body and inserting screws through the 110

brackets 23, flanges 19 and 13 and nuts 20. From the foregoing it will be seen that the end wall and reflector may first be assembled and then secured to the side body without 5 resorting to the use of external rivets, bolts or screws passing through the end wall.

Referring now to the front end of the head light, the flaring front 4 is suitably hinged to the front end of the side body 2 in the usual 10 manner. The outer end of this flaring extension is contracted to form an annular shoulder 25, the inner edge of which is bent inwardly at right angles to the shoulder portions to form an abutting flange 26 against which the 15 crystal or front glass rests. This glass is adapted to fit over the open end of the flaring front 4 and is secured in position against the flange 26 by means of an annular confining ring designated as a whole 27. The outer 20 margin of the ring is bent radially inward to form a confining flange 28. To provide space for a packing ring and also to give the structure a more finished appearance the ring is extended slightly beyond the glass 25 before it is bent inwardly to form the flange 28 and its extreme margin is turned inwardly at right angles, at 29, to meet the face of the glass. Between the glass and the flange 28 is an asbestos packing 30 which serves to 30 keep out dirt and moisture. The cylindric part of the confining ring telescopes over the outer end of the flaring front 4 and terminates in an annular bead 31 which adds to the finished appearance of the device.

35 In order to secure the confining ring to the front extension 4 and as an important feature of my construction, I provide a series of connecting brackets 32 riveted to the inner side of the ring 27 as shown clearly in Fig. 3 and 40 each provided with a threaded aperture 33. The ring is secured to the extension 4 by inserting suitable screws 34 through the shoulder 25 and brackets 32. It is of course obvious that these screws may be inserted 45 from the inside of the shell by swinging open the extension 4 on its hinges.

From the foregoing description it will be seen that I accomplish the several objects of the invention and produce a headlight casing 50 of extremely neat and finished appearance, devoid of many of the external rivets and projections which have heretofore been found indispensable, and furthermore so constructed that the reflector may be removed bodily with 55 the end closure of the casing by simply releasing the latter, thereby avoiding much of the danger incident to removing the reflector from its seat, and also avoiding the necessity of separately removing these parts.

60 It will be obvious that the details of construction may be somewhat modified without departing from the invention.

I claim as my invention:

1. In a headlight, the combination of a 65 side body member, an end closure member

having telescopic engagement with the side body, and means uniting said parts comprising a sheet metal joining ring interfolded with the out-turned margin of one of said members and extending radially within the 70 shell, internal radially extending projections on the other member extending adjacent to and in overlapping relation to said ring, and screw bolts extending through the ring and internal projections.

2. In a headlight shell, the combination of a side body member, an end closure member fitting one end of said side body, a radially inward extension united with one of said members, internal radially extending projections on the other member, and bolts extending through said radially inward extension and said internal projections and clamping the parts together.

3. In a headlight, the combination of a 85 side body member terminating at one end in a cylindric portion, an end closure provided with a cylindric marginal flange telescoping upon the corresponding part of the side body, a joining ring having a portion interposed between the overlapped portions of the side body and end closure, having its outer margin interfolded with the margin of the end closure and having a radially inward extending portion inside the 90 shell, one or more radially-inward extending projections upon the interior of the side body overlapping the radial portion of said joining ring, and screw bolts extending through said overlapping parts.

4. In a headlight, the combination of a side body member having a substantially cylindric end portion, an end-closure member provided with a cylindric portion telescoping the corresponding end of the side body member, a sheet metal joining ring extending between the telescoped portions of the side body member and end-closure member and interfolded with one of said members to form an external bead, internal projections 105 upon the other member, the inner part of said joining ring being extended radially inwardly and shaped to form an annular reflector seat, screw bolts inserted through the inner portion of said joining ring and a 110 plurality of said internal projections, a reflector seated against said joining ring, and a confining ring engaging the margin of the reflector and secured to the joining ring.

5. In a headlight, the combination with a 115 generally cylindric side body shell and an outwardly convex end closure having a cylindric marginal portion telescoping upon the end of the side body, of a joining ring having an intermediate portion extending 125 between the overlapped parts of the side body and end closure, having its outer margin turned outwardly and interfolded with an out-turned margin of the end closure 130 to form an external bead, having its inner

portion contiguous to the shell extended first radially inward and then formed into a concave reflector seat portion, a reflector seated against said ring, a confining ring having an angular portion overlapping and confining the margin of the reflector and a radial portion overlapping the radial portion of the joining ring, securing brackets secured to the interior of the side body and projecting adjacent to said confining ring, and screw bolts inserted through said brackets and the interposed portions of the confining and joining rings.

6. In a headlight casing, the combination 15 with a side body member provided at one of its end margins with a circumferential inset or rabbet, of a crystal-confining ring, constructed to telescope over the rabbet and provided upon its interior in register with 20 the rabbet with one or more bracket-like connecting members, and securing screws

inserted radially outward through the inner portion of the rabbet wall and into said connecting members.

7. In a headlight casing, the combination 25 with a side body member provided at its front end margin with an integral circumferential rabbet-shaped inset, of a crystal-confining ring having a cylindric portion telescoping the side and overlapping said 30 rabbet-shaped inset, and a radially in-turned margin forming a crystal-confining flange, means for uniting the crystal-confining ring to said rabbet-shaped inset, and the crystal having its margin interposed between the 35 front end margin of the side body and the confining flange of the confining ring.
